SHELVING AND PARTITION SUPPORT

Roy Franklin McMahan, near Louisville, Ky.

Application December 10, 1948, Serial No. 64,606

12 Claims. (Cl. 211—147)

1

This invention relates to an adjustable support for panels and shelf brackets to provide partitions for rooms, display cases or shelving, or the like.

It is an object of the invention to provide a type of support which is easily installed, and may serve as a support for adjustable cantilevers or shelf brackets and in which the ends of panels carried by said support conceal the support, thereby presenting the appearance of a continuous flat wall or partition.

A further object of this invention is to provide support means for a partition which is self-standing and requires no wall bracing for lateral support.

A further object is the provision of a shelf bracket for use with such a support which is inexpensive and is arranged to be secured to the support at various predetermined angles to the horizontal.

Still another object is the provision of a self-supporting display unit which is versatile and can be employed in a variety of combinations with shelving and bases.

Other objects of this invention will be apparent from the following description taken in connection with the accompanying drawing forming a part of this application, in which are illustrated preferred embodiments of the invention by way of example and wherein:

Figure 1 is a perspective fragmentary view of my invention showing a support carrying partitions and a cantilever type bracket arm.

Figure 2 is a section taken on plane 2, 2 of Figure 1 looking downward.

Figure 3 is a fragment of a blank perforated sheet ready to be formed into the vertical support upright shown in Figure 1.

Figure 4 is a fragmentary front elevational view of the support and partition members assembled for service.

Figure 5 is a side elevational view of Figure 4 without the partition and with a portion of a bracket arm assembled thereto.

Figure 6 is a side elevational view of the attachment end of the bracket arm.

Figure 7 is an end elevation of Figure 6.

Figure 8 is a view similar to Figure 6 of a modification.

Figure 9 is a sectional view similar to Figure 2 of a modification, and

Figure 10 is a perspective view showing a self-standing assembly embodying the invention.

Referring to the drawing, the upright designated generally by the numeral 10 may be made

from a single piece of sheet metal by bending and punching operations. For this purpose a sheet of the required length and width, a fragment of which is shown in Figure 3, is bent or folded along the broken lines *a* to *h* respectively to form a square or rectangular tubular portion bounded by walls 10A, 10B, 10C, 10D and 10E. The walls 10A and 10E provide a gap therebetween and have spaced webs 10G and 10F respectively extending therefrom, and which webs in turn end in wings or flanges 10J and 10H, respectively. Flanges 10J and 10H may terminate substantially in the planes of walls 10B and 10D respectively. Thus the wall 10A, web 10G and flange 10J form a laterally opening channel 11B, with the bottom walls 10G and 10F of the respective channels in spaced relation to provide a slot 12. Before bending the blank into the shape above described, the blank is punched to provide a double series of key apertures 13 and 14 near its edges, said apertures being oppositely positioned and being located to lie in the respective web and flange portions of the upright when the blank is bent, so that after the blank is bent 15 to shape the notched part 13B, 14B of each aperture will provide seats and lie in the web portions or bottom wall of each channel, and the slot parts 13A, 14A will lie in both the bottom and a side wall of each channel.

In the construction illustrated in Figures 1 to 7, the upright 10 is adapted to be held upright in any suitable manner as by attachment to a wall, and the upright is adapted to adjustably receive one or more shelf brackets indicated generally by 15. This bracket comprises a web 15A bent into a general serpentine shape and bent over at the top to provide a flange 15B which is also of serpentine shape and has apertures 15C therein. The base part 15D (Figure 6) of the bracket has an upper hole 16 therein in which is located a lateral projection in the form of a peg or dowel 17, and near the bottom of the web is located a hole 18 which receives a peg or dowel 19. The dowel 19 may be carried on a flexible arm 20 suitably pivoted at 21 on the web by a loose rivet. The shelf bracket is assembled to the upright by inserting the base 15D of the web into the slot 12 with the dowels 17 and 19 in alignment with pairs of spaced slots 13A, 14A until the dowels drop into the enlarged portions, seats 13B, 14B. The bracket is thus locked in position against displacement by any weight imposed thereon and dowel 19 cannot move rearward because it engages walls 10A, 10E.

Each flange portion 10J and 10H has tongues

22 Figs. 1, 2 and 9 extending into channels 11A and 11B respectively, which may be formed by striking inwardly a portion of the respective flanges. The channels 11A and 11B are of a width to receive the panels 23, 24 of plywood or other suitable material, and tongues 22 serve as stops to prevent the edges 26 of the panels from getting so close to the web 10G as to interfere with free movement of the dowels 17 and 19 in inserting or removing a shelf bracket. When assembled, the panels may be secured to the uprights by screws or bolts passing through suitable holes (not shown) in the parts 10A, 10J or 10E, 10H, and thus serve to conceal the tubular upright portion. The panels also serve to hold the uprights vertical and provide lateral support therefor. A pair of uprights 10, each carrying one or more brackets 15 may be provided, and the brackets support boards or sheets thereon to serve as shelves. The shelves may be vertically adjusted by shifting the shelf bracket to any pair of aligned slots 13, 14, and by locating such slots one inch apart, the shelves may be adjusted by increments of one inch.

Provision is made for supporting the shelf brackets at any predetermined angle to the horizontal. For this purpose a series of holes 18A, 18B, 18C, etc. are formed about pivot 21 as the center. The line joining holes 16 and 18 makes a right angle with the top surface of flange 15B, so that when the dowels are inserted in these holes the bracket 15 will be supported with its upper surface normal to the upright. The line joining holes 16 and 18A forms an obtuse angle so that by lifting dowel 19 out of hole 16 and shifting it to hole 18A, and inserting the bracket into an upright the top of the bracket will slope slightly upward. By shifting dowel 19 to either of holes 18B or 18C, the bracket and shelf carried thereby will slope downward at the corresponding angle. This latter arrangement provides a better display for certain items, particularly when the shelf is located above or at the line of sight. The flexible arm 20 enables this shifting to be done easily as the arm holds the dowel on a radius so that merely by the sense of feel and without fumbling the dowel can be positioned in the proper hole. In addition, the arm holds the dowel so it cannot be lost.

In the embodiment shown in Figure 8, the arm 20 has a hole in each end, one end being received on the dowel 17, and the other hole carrying the dowel 19. By slightly deforming the holes they may take a firm grip on the dowels. In this arrangement the holes 18, 18A, 18B, 18C, etc. are located about dowel 17 as the center, and the dowel 19 may be shifted as above described, the dowel 17 serving as a center or pivot for the arm 20.

In the modification illustrated in Figure 9 the upright made of two complementary bent plates having side walls 10B and 10D, inwardly turned walls 10A and 10E with webs 10G and 10F extending therefrom which terminate in flanges 10J and 10H. The rear edges of walls 10B and 10D are flanged, and at suitable intervals spacer plates 27 are welded to the rear flanges. This construction effects a saving in material and eliminates two bends in the manufacturing operation.

In the embodiment shown in Figure 10, which is designated to be self-standing, a base member 28, which may be shaped like the upright 10, has a slot 29 running its length. A web or plate 31 extends through said slot and into the slot 12 of

the upright member, and the web may be secured in position by spot welding, or in any other suitable manner. At the top, the base member is bent over to provide an apertured flange 32 and an apertured ear 33 may be provided along the front edge of the web. In this arrangement the panels 23 and 24 received in channels 11A and 11B of adjacent uprights and suitably secured in position, impart lateral rigidity to the uprights. A bottom shelf or deck 34 resting on the flanges 32 of adjacent members, and secured thereto, closes off the bottom. A base board 35 may be fastened to the flanges 33 at the front of the base members.

The uprights 10 may be of any desired height, and a display stand may be formed of any desired length, using two or more such uprights with their bases. Such a display stand is easily portable as it need not be secured to the building walls. Two such displays arranged back to back may form an island display in which the two sides are separated by the back paneling 23, 24, and the supporting tubular members are concealed thereby. By forming the base 28 four and one half inches high and supporting a one half inch plywood bottom 34, a standard five-inch front baseboard 35 may be employed to cover the front. The bottom may be arranged to provide a display shelf, or can be built in to provide a counter, showcase, or many other kinds of display equipment.

I claim as my invention:

1. A combined self-standing partition and shelf support comprising: an upright member having a bifurcated face; substantially parallel webs extending exteriorly from the edges of said bifurcation, each web of said upright having a series of seats therein and slots extending from said seats to the edges of said webs; and oppositely turned flanges at the edges of said webs providing with said face oppositely opening channels adapted to receive partitions therein.
2. A combined partition and shelf support as specified in claim 1 having inwardly struck tongues extending from the walls of said channels to provide partition stops.
3. A combined partition and shelf support as specified in claim 1 wherein said slots extend at least part way into said flanges.
4. A combined partition and shelf support as specified in claim 1 wherein walls extend rearwardly at the longitudinal edges of said bifurcated face, and means is provided joining the edges of said latter walls to provide a tubular upright.
5. A combined partition and shelf support as specified in claim 1 in combination with a bracket having a vertical web adapted to be received in said bifurcation and transverse projections extending from said vertical web and registering with a pair of opposed slots in said upright.
6. A combined self-standing partition and shelf support as specified in claim 1 in combination with a bifurcated generally tubular transverse base member; a web extending through said bifurcation in the base member and into the bifurcation in said upright, said web being secured in said upright and base member to hold said base member and upright in angular relation; said web member having an apertured flange at its top edge for reception of a shelf, and an apertured ear at the front end for attachment of a baseboard thereto.
7. A combined self-standing partition and shelf support as specified in claim 1 having a

transverse web passing into said bifurcation at the base of said upright and secured thereto, said latter web member having an apertured flange at its top edge for reception of a shelf, and an apertured ear at the front end for attachment of a baseboard thereto.

8. A support for shelves and partitioning material adapted for attaching to a wall or the like, comprising a vertical channel having a vertical slot and webs projecting outwardly from each side of said slot, each of said webs having a flange directed oppositely to each other and parallel to said wall to provide channels therewith for receiving partition material, and correlated seats in said webs and flanges adapted to receive and retain bracket members.

9. In a support for shelves and partitions, including in combination: a one-piece, vertical channel member formed from a rectangular sheet of metal into a substantially rectangular cross-section body having a longitudinal slot between juxtaposed exterior webs with flanges along the edges of said webs; said webs and flanges providing a vertical seat for said partition and having a plurality of opposing and horizontally disposed seats arranged in pairs for receiving bracket pins; and a bracket arm having an end formed to enter said slot and provided with transverse pins disposed in said end, each pin adapted to engage a pair of said seats.

10. A shelf support comprising: a pair of vertical webs arranged in spaced parallel relation to provide a slot; said webs having flanges directed oppositely to each other and correlated seats in said webs and flanges adapted to receive and retain bracket members therein.

11. A shelf support comprising a pair of vertical webs arranged in spaced parallel relation to provide a vertical slot; said webs having substantially horizontal slots in pairs in the forward edges terminating in depressed enlarged por-

tions; and a bracket member receivable in said vertical slot from the front and having laterally extending lugs receivable through said horizontal slots and adapted to seat in said enlarged portions to hold the bracket in weight supporting position.

12. In a shelf support: a one-piece vertical channel member formed from a rectangular sheet of metal into a substantially rectangular cross-section body having a longitudinal slot between juxtaposed exterior webs; said webs having a plurality of opposing and horizontally disposed seats arranged in pairs for receiving bracket pins; and a bracket arm having an end formed to enter said slot and provided with transverse pins disposed in said end, each pin being adapted to engage a pair of said seats.

ROY FRANKLIN McMAHAN.
